UNITED STATES PATENT OFFICE.

EDWARD H. WALKER, OF SOMERSET, PENNSYLVANIA.

RAILROAD-TIE.

1,195,302.

Specification of Letters Patent. Patented Aug. 22, 1916.

Application filed February 3, 1914. Serial No. 816,254.

To all whom it may concern:

Be it known that I, EDWARD H. WALKER, a citizen of the United States, residing at Somerset, in the county of Somerset and State of Pennsylvania, have invented a new and useful Railroad-Tie, of which the following is a specification.

The device forming the subject matter of this application is a metallic railroad tie.

10 One object of the present invention is to provide a novel form of fastening means for holding a rail upon the tie.

Another object of the invention is to improve the construction of the body portion 15 of the tie.

It is within the scope of the invention to improve generally and to enhance the utility of devices of that type to which the present invention appertains.

20 With the above and other objects in view which will appear as the description proceeds, the invention resides in the combination and arrangement of parts and in the details of construction hereinafter described 25 and claimed, it being understood that changes in the precise embodiment of the invention herein disclosed can be made within the scope of what is claimed without departing from the spirit of the invention.

30 In the accompanying drawings: Figure 1 is a top plan disclosing one form of the invention; Fig. 2 is a cross section on the line 2—2 of Fig. 1; Fig. 3 is a fragmental longitudinal section on the line 3—3 of Fig. 2; 35 Fig. 4 is a perspective of the actuating wedge; Fig. 5 is a cross section showing a modification; Fig. 6 is a cross section showing another modification; Fig. 7 is a top plan illustrating the modification shown in 40 Fig. 6, the line 6—6 on Fig. 7 illustrating the plane on which the section shown in Fig. 6 is taken; Fig. 8 is a fragmental longitudinal section taken on the line 8—8 of Fig. 6.

45 Referring to Figs. 1, 2 and 3, the body portion of the tie is fashioned from a double I beam, the same comprising a web 1, a bottom flange 2, a top flange 3 and an intermediate flange 21. The I beam is bent as at 4 and adjacent its ends, the beam is again bent as shown at 5 to bring the extremities of the beam into abutment as at 6, thus to form a closed loop. By the operation above described, the body portion of the tie is caused 50 to consist of opposed side portions 7 which are bent inwardly intermediate their ends

to form recesses 8, the side portions 7 of the body of the tie being bent inwardly adjacent their ends to form recesses 9. The recesses 8 and 9 receive the ballast and tend 60 to prevent the tie from moving endwise. In order to hold the side portions 7 of the body of the tie together, clips 10 are applied to the lower edges of the side portions. These clips 10 are disposed at the points of greatest 65 concavity in the recesses 8. Each clip 10 is provided at its outer ends with fingers 11 which engage the outer edges of the bottom flanges 2, and intermediate its ends, each clip 10 is provided with inner fingers 70 12 which engage the inner edges of the flanges 2. The fingers 11 and 12 may be corrugated slightly, in a vertical direction as shown at 14 in Fig. 3 so as to enhance their grip on the flanges 2. The space between the 75 side portions 7 of the body of the tie may be occupied by a concrete filler 15. Adjacent their upper edges, the side portions 7 of the body of the tie are united by braces 33, preferably taking the form of strips or 80 bars. These braces 33 are twisted to form internal shoulders 34 engaging the inner faces of the webs 1 of the side portions of the tie, the braces terminating in hooks 35 which pass through the webs 1 and engage 85 around the outer portions of the intermediate flanges 21.

Mounted on top of the body portion of the tie is a pair of tie plates. Each tie plate is denoted by the numeral 16 and is provided along its longitudinal edges with depending flanges 17 which, engaging the outer edges of the top flanges 3, serve to prevent the tie plates from moving transversely of the tie. The tie plates 15 are each provided 90 with upstanding flanges 18 extended transversely of the tie. It is between the upturned flanges 18 that the base of the rail 19 is lodged, as clearly shown in Fig. 3. The flanges 18 may be increased or decreased in 95 width as the gage of the track and the width of the base of the rail 19 may demand.

In order to hold down the rail 19 on the tie plate 16 a pair of fasteners is provided. The primary fastener is denoted by the numeral 20 and is equipped at its upper end with a projecting arm 22 which bears upon the base of the rail 19. In the lower edge of the arm 22 there is a recess 23 which accommodates the flange 18. The arm 22 is 100 provided with a laterally extended head 24, adapted to be engaged by a claw bar to 110

facilitate the removal of the primary fastener 20. The invention further includes a secondary fastener 26 which bears against the edge of the primary fastener 20, both of these fasteners passing through the tie plate 16, the top flange 3 and the intermediate flange 21. The secondary fastener 26 is equipped in its edge with a notch 27 receiving the tie plate 16 and the top flange 3, to the end that the secondary fastener may be prevented from moving endwise and in a vertical direction. In the abutting edges of the fasteners 26 and 20 cooperating notches 28 are formed. The notches 28 define an opening which receives a wedge-shaped cotter pin 29, split at its end to form fingers 30. The side faces 31 of the wedge 29 converge and the top and bottom faces 32 of the wedge converge also.

20 In practical operation, the tie plate 16 is mounted on the tie and its downturned flanges 17 are engaged with the outer longitudinal edges of the top flange 3 as shown in Fig. 2. The rail 19 is then mounted in place as shown in Fig. 3, the base of the rail being engaged between the upstanding flanges 18 on the tie plate. Then the secondary fastener 26 is inserted, its notch 27 engaging the tie plate 16 and the flange 3, so that the secondary fastener cannot move endwise. The primary fastener 20 is then mounted in place as shown in Fig. 3. The wedge-shaped cotter pin 29 is inserted into the opening formed by the notches 28, and is driven to a firm seat, the fingers 30 of the cotter pin being bent over if desired. Since the wedge 29 tapers both vertically and horizontally, the primary fastener 20 is crowded transversely so that its head 24 overhangs the base of the rail 19, and, by the operation of the wedge 29, the same engaging the fixed fastener 26, the fastener 20 is forced downwardly so that its head 24 has a firm bearing on the base of the rail 19. The fastener 20 is made of malleable metal and after the said fastener has been seated as above described, its lower end may be bent to form a lateral foot 25 engaging the lower edge of the intermediate flange 21, as Fig. 3 will clearly show. At this point it may be stated in connection with the primary fastener 20 and its foot 25, that the concrete filler 15 may or may not be resorted to and, if desired, the center of the tie may merely be filled in with ballast.

60 In Fig. 5 a modified form of the invention is shown, the structure in all vital particulars being a duplicate of that shown in Fig. 2. In Fig. 5 the web is depicted at 36, the bottom flange at 37, the top flange at 38, the clip at 39, the tie plate at 40, and the brace at 41, the same being provided with internal shoulders 42 and with external hooks 43 as hereinbefore set forth. The hooks 43 engage the intermediate flanges 44. These

flanges 44 exist only upon the outer faces of the webs 36 and are the distinguishing characteristics of this form of the invention.

Passing to the modification shown in Figs. 6, 7 and 8, the body portion of the tie comprises an inverted channel 45, the side walls of which slope toward each other as they extend downwardly. The side walls 46 along their lower edges are equipped with outwardly projecting feet or flanges 47. The clips are indicated at 48 and each clip includes internal fingers 49 and external hook-shaped fingers 50. The internal fingers 49 bear against the lower edges of the walls 46 and the external fingers 50 are engaged around the edges of the feet 47. The side walls 46 of the channel 45, but not the top portion thereof, are bent inwardly to form recesses 51 and it is in these recesses that the clips 48 are mounted. Other clips 52, formed like the clips 48, may engage the laterally extended feet or flanges 47, relatively near to the ends of the tie, as Fig. 8 will show. The tie plate is indicated at 53 and is equipped with the depending flanges 54 and the upstanding flanges 55, hereinbefore described. The rail 56 rests on the tie plate between the flanges 55. The primary fastener is shown at 57 and the secondary fastener at 58. The wedge member is depicted at 59. In this form of the invention, the fasteners 57 and 58 terminate in their lower ends in bendable feet 60 engaged in an opening 61 in the wall 46.

Having thus described the invention, what I claim is:

1. In a railroad tie, a body having an opening; a rail holding fastener movable transversely in the opening; a wedge engaging the fastener to move the fastener transversely; and an abutment for the wedge; the fastener having a bendable end extended laterally and engaged beneath a portion of the body to hold the fastener against upward movement.

2. In a railroad tie, a body; a pair of fasteners one of which is interlocked with the body, the other of which is a rail holding fastener and is adjustable both horizontally and vertically, means engaging both fasteners for moving the rail holding fastener horizontally, the rail holding fastener being provided with a bendable end which is extended laterally and is engaged beneath a portion of the body to retain the rail holding fastener against upward movement.

3. In a device of the class described, a tie having upper and lower flanges provided with openings; a tie plate resting on the tie and having openings aligned with the openings in the flanges; a rail on the tie plate; pairs of fasteners passing through all of the openings, one fastener of each pair being engaged with one flange against vertical movement, and one fastener of each pair

engaging the rail; and means interposed between the fasteners of each pair for producing relative movement therebetween.

4. In a rail fastening means, a tie including a body having an opening; a tie plate resting on the tie and provided with an upstanding flange; a rail resting on the tie plate and engaged by the flange; a fastener located in the opening and including a laterally extended head engaging the rail, the head being cut away in its lower edge

to clear the flange; a wedge coöperating with the fastener to force the fastener downwardly; and a fixed abutment with which the wedge engages.

15

In testimony that I claim the foregoing as my own, I have hereto affixed my signature in the presence of two witnesses.

EDWARD H. WALKER.
